UNITED STATES PATENT OFFICE.

CHARLES C. PHILLIPS, OF OWENSBORO, KENTUCKY, ASSIGNOR TO THE PHILLIPS AUTOMATIC SIGNAL CO., OF OWENSBORO, KENTUCKY.

TROLLEY CUT-OUT.

No. 906,279.

Specification of Letters Patent.

Patented Dec. 8, 1908.

Application filed May 9, 1907. Serial No. 372,674.

To all whom it may concern:

Be it known that I, CHARLES C. PHILLIPS, a citizen of the United States, residing at Owensboro, in the county of Daviess and 5 State of Kentucky, have invented new and useful Improvements in Trolley Cut-Outs, of which the following is a specification.

This invention relates to trolley cut-outs, the object of the invention being to provide 10 a hanger for trolley wires whereby upon the breakage of the trolley wire at any point, the broken portion thereof which remains attached to the hanger, will be thrown out of circuit or electrical connection with the 15 main current, thereby preventing any possibility of injury to pedestrians, animals, etc., coming in contact with such broken wire.

With the above general object in view, 20 the invention consists in the novel construction, combination and arrangement of parts hereinafter more fully described, illustrated and claimed.

In the accompanying drawings, Figure 1 25 is a view in elevation of the automatic cut-out of this invention. Fig. 2 is an enlarged detail cross-section through the same, on line 2—2, Fig. 1. Fig. 3 is a view similar to Fig. 1, showing the action of the device upon 30 the breakage of a wire.

The trolley cut-out contemplated in this invention consists of what may be termed a hanger or bracket 1 embodying three downwardly extending legs 2, 3 and 4, either 35 formed separately or integrally, as may be found expedient. The lower ends of these legs are all located in about the same horizontal plane and the ends of the wire or conductor shown at 5 and 6 are pivotally connected therewith as shown at 7, while under the preferred embodiment of this invention, the portions of the conductors lying just outside of the pivotal points 7 are weighted, as shown at 8, to insure the interruption of the 40 current, as will hereinafter appear. The lower end of the intermediate leg 4 carries a trough or gutter-like conductor section 9 having the oppositely projecting seats or 45 rests 10, the upper sides of which are caved in the form of gutters to receive the inner ends of the conductors 5 and 6, as

shown in the drawings, the said conductor ends terminating short of each other, as indicated in Figs. 1 and 2. The conductor section 9 is composed of material having the 55 necessary electrical conductivity and is preferably composed of soft metal such as copper and provided at opposite sides with upwardly extending soft metal fingers 11, which are bent to embrace and lie in contact 60 with the upper sides of the conductor ends, as indicated in Fig. 2, thus giving increased contact or bearing between the conductor ends and the conductor section 9. The fingers or lugs 11 are sufficiently soft to bend 65 outwardly under the force of the weight acting on the conductor 6, as for instance, when the latter is broken to permit the conductor to move to open position, as shown at the right of Fig. 3. The hanger is provided with 70 one or more eyes 12 or their equivalent by means of which the hanger may be supported on a suitable pole, cross-arm or other form of overhead support.

The conductor section 9 forms a part of 75 the conductor under ordinary conditions and it will be seen that when one of the wires is broken as shown in Fig. 3, the inner extremity thereof lying in contact with the conductor section 9 swings upward, being assisted by the weight 8, and in this way the 80 circuit is broken and no current is transmitted through the broken wire.

I claim:

1. In an automatic cut-out, the combination of a hanger comprising oppositely-extending outer arms and a centrally depending arm, current-conducting wires having their meeting ends disposed at opposite sides of the central arm, means movably supporting the wires on the lower extremities of the outer arms, a horizontal trough-like member in which the extremities of the wires rest, bendable lugs rising from opposite sides of the member and adapted to embrace the extremities of the wires by being bent over the latter, and means for detachably connecting the member to the lower extremity of the central arm.

2. In an automatic cut-out, the combination of a bracket, separate conductors pivotally mounted on the bracket, a member nor-

mally supporting the extremities of the conductors and detachably secured to the bracket, said members being of U-shaped cross-section, and readily bendable lugs of
5 soft metal arranged to engage over the conductors for holding the latter in contact with the member.

In testimony whereof, I affix my signature in presence of two witnesses.

CHARLES C. PHILLIPS.

Witnesses:

FRANK KATTERJOHN,
RICHARD PENNELLY.
